CASING FOR AN ELECTRIC HEATER

Allen Leighton, Chatham, N.J., assignor to Spartan
Electric Radiator Corp., Linden, N.J.

Filed July 2, 1962, Ser. No. 70,764

Term of patent 14 years

(Cl. D81—10)

FIG. 1

FIG. 2

FIGURE 1 is a front perspective view of my casing for an electric heater showing my new design.

FIGURE 2 is a cross-sectional view of my casing for an electric heater shown in FIGURE 1 taken along line 2—2.

The end not shown is substantially the same in appearance as that shown in FIGURE 1, and the bottom and rear of the casing are plain and closed.

I claim:

The ornamental design for a casing for an electric heater, substantially as shown and described.
